UNITED STATES PATENT OFFICE

JAMES MACMARTIN, OF ALBANY, NEW YORK

RAILROAD TIE

Application filed September 14, 1929. Serial No. 392,699.

My invention relates to metallic railway ties, and particularly to those kinds in which resilient insulating blocks, for example, wood, are used in connection with the metallic tie proper.

The disadvantages of the ordinary wooden tie are many. Its useful life is relatively short, due to weathering and rotting, and, as the tie becomes old, it fails to hold securely

10 by the spikes or screws which hold down the rails. Moreover, with the depletion of our forests, the cost of replacements is constantly increasing. However, there are some advantages attending the use of wooden ties.

15 They not only cushion the pounding effect of the trains and hence make for easier riding, but they also act as electrical insulators so that there is comparatively small leakage from the track circuits.

20 It is the object of my invention to device a composite tie which combines the advantages of steel for durability and wood for resiliency and insulation. A further object is to provide a tie in which the wood portions 25 may be removed and replaced with comparative ease.

With these objects in view, my invention includes the novel elements and the combinations and arrangements of elements described below and illustrated in the accompanying drawings, in which—

Fig. 1 is a partial plan view of a railroad track with my novel tie;

Fig. 2 is a vertical longitudinal sectional view taken on the line 2—2 of Fig. 1;

Fig. 3 is a fragmentary vertical cross sectional view taken on the line 3—3 of Fig. 1;

Fig. 4 is a view similar to Fig. 3 taken on the line 4—4 of Fig. 1;

40 Fig. 5 is a fragmentary view similar to Fig. 2 taken on the line 5—5 of Fig. 6, and showing a modified form of tie;

Fig. 6 is a sectional view taken on line 6—6 of Fig. 5; and

45 Fig. 7 is a fragmentary view similar to Fig. 5 but showing a further slight modification.

Referring to the drawings, 1 are longitudinal irons, preferably used steel rails, but which may be of any suitable structural

shapes such as channels or I beams. These longitudinal irons are secured in position, relative to each other, by steel cross pieces, 2, shown as welded to the longitudinal irons at 11, but which, however, may be attached by 55 any other suitable means, such for example, as rivets passing through flanges provided on the cross pieces and abutting the webs of the rails.

The cross pieces, 2, have their upper edges 60 bent over to form flanges, and, their sides and bottoms are cut to fit the shape of the longitudinal irons.

Above the irons, 1, between the cross pieces, 2, and under the flanges of the latter are wood 65 wearing blocks, 3, (preferably of oak). These wearing blocks, 3, are preferably only partly supported by the irons, 1, though the latter may entirely support the wearing blocks, if desired.

Beneath the wearing blocks, 3, and between the longitudinal irons, 1, are wood bed blocks, 4, which preferably only partly support the wearing blocks, 3, but, which may, if desired, form the entire support for the wearing 75 blocks. The distance between the longitudinal irons, 1, which limits the width or thickness of the bed blocks, is sufficient to permit the staggered rail fastenings, 5, to enter the bed blocks, 4, and not be so close to the irons, 1, as to cause a leakage of electricity from the track circuits to the longitudinal irons, 1. 80

The irons may be further secured by steel cross pieces or braces, 6. They are of suitable size, and are welded or riveted to the longitudinal irons, 1, to prevent relative longitudinal movements of the irons, 1. The cross pieces, 6, may be located in any suitable place for the purpose intended, and there may be one or more of them.

The track rails 7 are supported on top of the wearing blocks, 3, and are secured to the steel tie, by means of spikes or screws, 5, extending into the wood elements. Screw fastenings, if used, need not extend through the 95 wearing block. If desired, tie plates may be placed between the base of the rails, 7, and the tops of the wearing plates, 3.

If old rails are used for the longitudinal irons their top surfaces may be planed or 100

milled, as shown at 9, to form a bearing for the wearing blocks, 3. Instead of planing or milling the rails, it is obvious that flat pieces of steel may be attached to the irons by any suitable means.

The wearing and bed blocks are easily removable and renewable; the wearing blocks, 3, by horizontal sliding, and the bed blocks by vertical lifting. The blocks should be of such size as to fit tightly in the spaces provided and they will be held firmly in place by the swelling of the wood against the longitudinal irons of the tie when the spikes are driven into place.

15 In Figs. 5 and 6 is shown a modification of my tie. Here, the bed block and wearing block are a single piece, 15, secured at one end by strap, 16, which may be formed from a channel iron, and is removably fastened to irons, 1, by bolts, 19. The piece, 15, is secured at the opposite end by cross piece, 2. The longitudinal irons, 1, are spaced further apart than those shown in Figs. 1 to 4 so that the block, 15, will have sufficient width or thickness to provide an adequate bearing area for the rail. This width should be at least sufficient to support a tie plate, 17. Block, 15, while easily removable and renewable, should fit snugly in the space provided so that the spikes will also cause a sufficient swelling to hold it securely in place.

30 In Fig. 7, is shown a further modification in which cross piece, 18, has its flange so arranged that the flange, as well as the rest of the cross piece, may be welded or fastened to the iron, 1. This iron may be milled if desired as shown at 20 or if desired have a flat iron secured to the top of the longitudinal iron, 1, so that the flange, 18, may have close contact

40 with rail, 1.

While I have described and illustrated my invention in its preferred embodiment only, it is to be understood that the words which I have used are words of description rather than of limitation, and that changes within the purview of the appended claims may be made without departing from the true scope and spirit of my invention.

50 For example, instead of wood blocks, I could use blocks of fiber rubber, rubber composition, or any material which combines the necessary resiliency with insulating properties, and I wish it to be clearly understood that my invention contemplates the use, as described in respect of wood, of other materials having the necessary resiliency and insulation properties.

What I claim is—

60 1. A railway track structure comprising ties formed of longitudinally extending metallic members, metallic cross pieces secured to said members, said cross pieces being provided on their upper edges with flanges extending toward each other to form a chan-

nel therebetween, and a wearing block inserted in said channel.

2. A railway tie comprising longitudinal irons secured together, transverse, flanged elements attached to said irons, and rail supporting wearing blocks secured in place by said transverse elements.

3. A railway tie comprising a plurality of longitudinal elements, transverse flanged elements securing said longitudinal elements together, and rail supporting, wearing blocks secured between said flanged elements.

4. A railway tie comprising longitudinal members, transverse members attached to said members and provided on their upper edges with flanges, and wearing blocks having physical characteristics differing from said longitudinal and transverse members secured in place by said longitudinal members.

5. A railway tie comprising longitudinal members, connecting means including flanged elements welded to said members and wearing blocks of insulating material supported by said members and secured in place by said connecting means.

6. A railway track structure comprising two longitudinal irons secured together in spaced relation, cross pieces anchored to said irons and provided above said irons with flanges extending toward each other and forming a channel, and wearing blocks slidably inserted in said channel and supported by said irons.

7. A railway tie comprising two longitudinal metallic members secured together, transverse elements locked between and secured to said members and provided at the top with flanges extending toward each other, bed blocks between and supported by the longitudinal members, and wearing blocks slidably inserted between said flanges and supported by the bed blocks and longitudinal members.

8. The tie as set forth in claim 7, in which the bed blocks and wearing blocks are of insulating material.

9. In a railway tie, the combination with a plurality of spaced longitudinal metal members, of insulating blocks between said members, wearing blocks supported on said insulating blocks, and means including flanged connecting elements securing the members and wearing blocks together.

10. In a railway tie, the combination with a plurality of spaced longitudinal members, of insulating blocks between said members, wearing blocks supported on said insulating blocks and covering the longitudinal members and means securing the members and wearing blocks together.

11. In a railway tie, two longitudinally extending track rail sections located side by side, means for securing said sections together and wearing blocks extending between

said sections and supported on the flanges thereof.

12. In combination, a tie comprising two longitudinally extending track rail sections located side by side, means for securing said sections together, wearing blocks extending between said sections and supported on the flanges thereof and track rails mounted on said wearing blocks.
